UNITED STATES PATENT OFFICE.

FRED M. ALLEN, OF AUBURN, RHODE ISLAND.

FINGER-RING.

No. 795,382.

Specification of Letters Patent.

Patented July 25, 1905.

Application filed April 26, 1905. Serial No. 257,438.

To all whom it may concern:

Be it known that I, FRED M. ALLEN, a citizen of the United States, residing at Auburn, in the county of Providence and State of Rhode Island, have invented a new and useful Improvement in Finger-Rings, of which the following is a specification.

This invention has reference to an improvement in finger-rings, and more particularly to an improvement in detachable signet-plate finger-rings.

The object of my invention is to improve the construction of detachable or interchangeable signet-plate finger-rings, whereby the signet-plate is positively locked in the ring and readily detached from the ring when required without the use of a special tool for the purpose.

My invention consists in the peculiar and novel construction of a finger-ring having an oval box-shaped head in the bottom of which, adjacent one end, is an off-center hole, an internal annular ledge on the side wall of the head having an off-center opening, one side of which is beveled adjacent the hole in the bottom of the head, a signet-plate shaped to fit the head and rest on the annular ledge, said plate being adapted to have a letter or monogram on its face, and a spring-wire locking-arm rigidly secured adjacent one end to the under side of the plate in a position for the fixed end to first enter under the ledge and then for the free end to engage with the beveled edge of the opening in the ledge and snap under the ledge through the opening, thus locking the plate to the ring, as will be more fully set forth hereinafter.

Figure 1 is a side view of my improved finger-ring. Fig. 2 is a face view of the ring, showing the detachable signet-plate. Fig. 3 is a transverse sectional view taken on line 3-3 of Fig. 1 looking at the under side of the head. Fig. 4 is an under side view of the signet-plate removed from the ring and showing the spring-wire locking-arm. Fig. 5 is an enlarged sectional view taken on line 5-5 of Fig. 1 through the head, showing the locking-arm in the head in the locked position. Fig. 6 is an enlarged sectional view taken lengthwise through the head on line 6-6 of Fig. 2, showing the signet-plate locked in the head of the ring; and Fig. 7 is an enlarged detail sectional view taken on line 7-7 of Fig. 2, showing the means for unlocking and removing the signet-plate from the ring.

In the drawings, *a* indicates a finger-ring,

b an interchangeable signet-plate, and *c* the pointed end of a pin or similar article, as shown in Fig. 7.

The ring *a* has an oval box-shaped head *a'*, in the bottom of which, adjacent one end, is the off-center hole *a²* and on the inner side wall of the head the annular ledge *a³*, having the off-center opening *a⁴*, one side of which has the beveled surface *a⁵*, as shown in Figs. 5 and 7. Otherwise the ring may be of any design or configuration desired.

The signet-plate *b* is shaped to fit the head *a'* of the ring and rest on the ledge *a³* flush with the face of the head. The face of the signet-plate is adapted to have a letter or monogram. A frame *b'* is constructed to have the loop *b²* at one end and the slot *b³* in the opposite end. A spring-wire arm *b⁴* is secured adjacent the end *b⁵* in the loop *b²* of the frame *b'* by solder or other means. This spring-arm *b⁴* extends centrally approximately the length of the plate, the free end *b⁶* passing through the slot *b³* in the frame *b'*, the length of the slot allowing a limited side movement only to the free end *b⁶* of the spring-arm. The frame *b'* is now secured to the under side of the plate by solder or other means in a position to bring the spring-arm *b⁴* on a central line lengthwise of the plate, as shown in Fig. 4. The fixed end *b⁵* of the arm is adapted to go under the ledge *a³* and the free end *b⁶* to pass through the opening *a⁴* and snap under the ledge, thus securely locking the plate to the ring.

After a dealer has fitted a buyer with the size of ring desired a different letter or monogram is usually required. The signet-plate *b* is easily removed from the ring by inserting the pointed end of a pin or similar article into the hole *a²*. The pointed end of the pin engages with the free end *b⁶* of the spring-arm *b⁴* and moves it sidewise into the opening *a⁴* in the ledge against the spring tension of the arm, when a further inward movement of the pin will push the plate out of the ring. The new plate is now inserted by placing the fixed end *b⁵* of the spring-arm *b⁴* under the ledge *a³* opposite the hole *a²* and forcing the plate into the head of the ring. As the plate enters the head of the ring the free end of the spring-arm *b⁴* strikes the beveled surface *a⁵*, which forces the end of the arm sidewise into and through the opening *a⁴*, when it snaps under the ledge *a³*, as shown in Figs. 5 and 7, and automatically locks the signet-plate to the ring.

It is evident that the head of the ring and the signet-plate could be of any configuration desired without materially affecting the spirit of my invention.

Having thus described my invention, I claim as new and desire to secure by Letters Patent—

1. A finger-ring having a box-shaped head in the bottom of which is an off-center hole adjacent one end and a ledge on the inner side walls of the head having an opening one side of which is beveled, a signet-plate having a spring-arm, and means for securing one end of the spring-arm to the under side of the plate in a position for the fixed end of the arm to go under the ledge and for the free end of the arm to first strike the beveled surface, pass through the opening in the ledge, and snap under the ledge, as described.

2. A finger-ring having a box-shaped head in the bottom of which is an off-center hole adjacent one end and a ledge on the inner side walls of the head having an opening one side of which is beveled, a signet-plate, a spring-wire arm, a frame having a loop, means for securing one end of the spring-wire arm in the loop of the frame, and means for securing the frame to the under side of the signet-plate in a position for the fixed end of the spring-arm to go under the ledge and for the free end of the spring-arm to first strike the beveled surface, pass through the opening in the

ledge and snap under the ledge, thereby locking the signet-plate to the ring, as described.

3. The combination of a finger-ring *a* having the box-shaped head *a'* in the bottom of which is the off-center hole *a²* adjacent one end, and the ledge *a³* on the inner side wall of the head having the opening *a⁴* one side of which has the beveled surface *a⁵*, a signet-plate *b* shaped to fit in the head of the ring, a frame *b'* constructed to have the loop *b²* on one end and the slot *b³* in the opposite end, a spring-wire arm *b'*, means for securing the spring-arm *b⁴* adjacent one end in the loop *b²* of the frame in a position for the free end *b⁵* to extend through the slot *b³* in the frame, and means for securing the frame *b'* to the underside of the signet-plate *b* in a position for the fixed end *b⁶* of the spring-arm to go under the ledge *a³* and for the free end *b⁵* of the arm to first strike the beveled surface *a⁵*, pass through the opening *a⁴* in the ledge and snap under the ledge, thereby locking the signet-plate in the head of the ring, as described.

In testimony whereof I have signed my name to this specification in the presence of two subscribing witnesses.

FRED M. ALLEN.
